Assistant Examiner — Bryan C Gusman

(57) CLAIM

I claim the ornamental design for a grooming desk, as shown and described.

DESCRIPTION

FIG. 1 is a front perspective front view of a grooming desk, showing my new design;

FIG. 2 is a front view thereof;

FIG. 3 is a rear side view thereof;

FIG. 4 is a left side view thereof;

FIG. 5 is a right side view thereof; and,

FIG. 6 is a top view thereof.

The broken line portion of the figure drawings is included to show portions of the article that forms no part of the claimed design.

1 Claim, 6 Drawing Sheets
